(57) **CLAIM**

The ornamental design for an electrical weapon as shown and described.

DESCRIPTION

FIG. 1 is a front perspective view of an electrical weapon showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the remainder of the electrical weapon form no part of the claimed design. The unshaded areas between the broken and solid lines form no part of the claimed design.

1 Claim, 7 Drawing Sheets
